UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

LINE-CASTING MACHINE.

1,081,047.

Specification of Letters Patent.

Patented Dec. 9, 1913.

Application filed December 30, 1911. Serial No. 668,650.

To all whom it may concern:

Be it known that I, GEORGE P. KINGSBURY, a citizen of the United States, and a resident of the borough of Brooklyn, county of Kings, and State of New York, have invented 5 a new and useful Improvement in Line-Casting Machines, of which the following is a specification.

My invention relates to line casting machines of the Mergenthaler type, as shown 10 in Letters Patent of the United States No. 436,532, and kindred machines, in which circulating matrices are employed.

In practice certain letters of the alphabet, 15 such as e, i, etc., are used with much greater frequency than others. It is, therefore, a common practice to devote two or more channels of the magazine to matrices containing the same character, and to provide 20 in connection with the finger keys which release the matrices mechanism to cause their release from the associated channels in a definite order or succession, as shown, for example, in Letters Patent of Great Britain No. 19,017 of the year 1905, and in Letters Patent of the United States No. 658,740, dated September 25th, 1900.

The object of my invention is to provide 25 a more simple and direct mechanism through which matrices may be discharged from two adjoining magazine channels alternately.

To this end, it consists in combining with 30 two escapements, a single reed or keyboard connection, and an intermediate shifting member through which the reed actuates the two escapements alternately.

In the drawings: Figure 1 is a vertical 35 section from front to rear through the escapement mechanism combined with my improved device. Fig. 2 is a rear elevation of the same.

Referring to the drawings: A represents 40 an inclined longitudinally channeled magazine adapted to receive and guide the matrices B.

C, C' represent escapement levers pivoted 45 at c and having at opposite ends two lips which, by the vibrations of the escapement, are projected upward alternately into the magazine to control the matrices and release them one at a time.

D is a spring which holds the escapement 50 normally in the position shown.

Matrices containing the same character

will be carried in the two channels controlled by the escapements C and C'.

So far as described the parts are similar to those now in commercial use.

E, E' are two arms or levers mounted in the main frame on horizontal pivots, and 60 adapted to act upward against the respective escapements for the purpose of operating them.

F is an escapement actuating reed, vertically guided, and having its upper end bifurcated or formed with two arms, to act on the respective levers E, E'. This reed F will be connected by any suitable devices with a finger key representing the matrix character in the two channels, for instance, 70 mechanism such as shown in Letters Patent of the United States to Philip T. Dodge, No. 530,931.

The upper ends of the reed F do not act 75 directly on the levers E, E', but communicate motion to them alternately through an intermediate dog G. This dog, of T-form, is provided at the upper end with a suspending pivot or trunnion g, mounted to travel in a V-shaped groove in the stationary plate J, the lower side of this groove being formed by a spring H, secured at one end only by a screw h, and bent upward into the groove or notch as shown. The form and arrangement of the parts is such that 80 this dog is lifted by the two ends of the reed F alternately, and caused by the spring or switch H to turn to the right or left, so that its lower end stands normally under the respective levers E, E' and over the corresponding ends of the reed F. When the 85 dog is in the position shown in Fig. 2 it will be lifted by the left arm of the reed F, and will communicate motion through the overlying lever E to the escapement 90 C, thereby effecting the delivery of a matrix from one of the channels. As the dog rises during this action its upper end passes over the raised point of the spring H; and when the reed descends the dog falls to the 95 position shown in dotted lines, with its end between the right hand lever E' and the right arm of the reed F, so that when the reed is again raised the dog will leave the lever E at rest and impart motion 100 to the lever E' to the escapement C'. It will be seen, therefore, that the successive actions of the reed cause the dog G

to shift to and fro, right and left, so as to communicate motion from the reed to the levers E, E' and the connecting escapements, alternately.

5 It will be obvious to the skilled mechanic that the form of the dog, and the details, may be materially modified within the range of mechanical skill without departing from the limits of my invention. It will 10 also be understood that the dog G instead of operating on the escapements through the levers E, E' may be located between them and arranged to operate directly upon them.

15 While I prefer to employ the form of escapement herein shown, I may employ escapements such as shown in Letters Patent of the United States No. 436,532, or escapements of any equivalent form.

20 Having described my invention, what I claim is:

1. The combination of two escapements, an actuating reed, and an intermediate independently supported dog to communicate 25 motion from the reed to the two escapements alternately, said dog arranged to move laterally from one operative position to another under the influence of the reed.

2. In combination, the two escapements, 30 the levers for communicating motion thereto, the forked reed, the intermediate dog operated thereby, and means for shifting the dog to the right and left as it is operated by the reed.

3. In combination, the two escapements C 35 and C', actuating levers E and E', the reed, the laterally movable and independently supported dog located between the reed and the levers, and a switch mechanism whereby the operation of the reed shifts the dog into operative relation to the two levers alternately. 40

4. As a means of communicating motion to two escapements alternately, a lifting reed, a pendant dog, and a switch by which the dog is supported and thrown to the right 45 and left by successive movements of the reed.

5. In combination with the reed, the pendant dog G, the grooved or notched plate J, and the spring switch H, whereby the actuation of the reed shifts the dog from one operative position to another. 50

6. The combination of two escapements, actuating means therefor comprising two distinct operating members, one for each 55 escapement, and a device controlled by said actuating means to interpose itself between one or the other of the said escapements and the corresponding operating member, to establish the connection between the escapement and the actuating means. 60

In testimony whereof I hereunto set my hand this 20th day of December, 1911, in the presence of two attesting witnesses.

GEORGE P. KINGSBURY.
